UNITED STATES PATENT OFFICE.

PAUL DIETZ, OF PHILADELPHIA, PENNSYLVANIA.

LABEL-PRINTING MACHINE.

Application filed September 29, 1923. Serial No. 665,580.

To all whom it may concern:

Be it known that I, PAUL DIETZ, a citizen of the United States, residing in Philadelphia, Pennsylvania, have invented a Label-
5 Printing Machine, of which the following is a specification.

One object of this invention is to provide a relatively simple, durable and substantial hand operated machine primarily designed 10 for printing labels, and the invention especially contemplates a device by which perfect work may be produced by relatively unskilled labor.

Another object of my invention is to provide 15 a printing machine which may be operated by hand at high speed, which shall be clean, convenient and not likely to get out of order or require skilled attention.

A further object of the invention is to provide 20 a printing machine in which the power for moving the label-carrying bed toward the type housing to accomplish the printing shall be provided by a hand controlled spring, and in which the arrangement of parts is such that the printed labels shall be automatically discharged upon a receiving tray or platform.

I also desire to provide a printing machine with novel means for controlling and 30 actuating its bed, including conveniently placed elements for releasing said bed to perform the printing and for resetting the bed after the printing.

Another object of the invention is to provide 35 a machine of the character described with simple and readily accessible means for holding the type;—the invention including convenient means for adjusting or changing the type and for causing an ink ribbon to be fed over the same at each operation of the machine.

I also desire to provide a machine of the character noted with a table for the labels to be printed which table may be conveniently adjusted to serve as a lock for the movable bed.

These objects and other advantageous ends, I attain as hereinafter set forth, reference being had to the accompanying drawings, in which,

Fig. 1 is an elevation of one side of a printing machine constructed in accordance with my invention;

Fig. 2 is a plan of the machine shown in Fig. 1;

Figs. 3 and 4 are vertical sections taken respectively on the lines 3—3 and 4—4, Fig. 2;

Figs. 5 and 6 are vertical sections respectively on the lines 5—5 and 6—6, Fig. 4; and,

Fig. 7 illustrates a modified form of control levers.

In the above drawings, 1 represents a base structure preferably in the form of a hollow casting of rectangular outline provided with hemispherical or other suitable form of feet 2—2 of rubber or other suitable material within the hollow of the base structure 1, I preferably mount a slideable drawer 3 for the reception of a block 4 of wood having vertical cavities 5 therein designed to hold the various types used in the machine. While the body of the drawer 3 is preferably of sheet material, I preferably provide it with a cast front plate 6 fastened by suitable means and having a central knob or handle 7 whereby the drawer may be manipulated.

The base casting 1 has projecting vertically upward therefrom three posts or standards, of which two, indicated at 8, are at opposite sides of the front of the machine while the third post 9 is at the middle of the back. These posts at their upper ends carry a flat topped platform 10 which is preferably though not necessarily held to the posts by screws of which one is indicated at 11 in Fig. 3. Extending upwardly from the rear part of the platform is a relatively heavy rigid standard or frame 12 of substantially rectangular outline having a flat perpendicular front face against which is mounted a type housing 13. The lower portion of the frame 12 is laterally extended upon the top of the platform 10 to which it is rigidly held by screws 14.

The type housing preferably has the form of a horizontally elongated rectangular box open on its front vertical face and made up of a bottom member 15, two side members 16—16 and a top member 17. The latter has threaded into it two clamping screws 18—18 operative upon a clamping bar 19 whereby the type, with any suitable number of spacing strips, may be firmly clamped

therein. With the above arrangement of type housing, several lines of type may be rigidly supported with their faces all in a substantially vertical plane and with their 5 rear ends lying against the flat front face of the frame or plate 12 which serves as the bottom of said type housing. As shown in Fig. 3, the platform 10 is formed with a downwardly flanged, laterally elongated 10 central opening 20, adjacent the opposite ends of which are bearings 21 projecting upwardly from the top of said platform and having journaled in them spindles 22 and 23 respectively constituting the pivots or trunnions for a flat faced bed 24. This latter is designed to be movable from a position in which its flat face is substantially vertical and immediately adjacent the plane of the face of the type housing 13, to a position 15 in which, as shown in Fig. 3, its flat face is substantially horizontal, and for the purpose of moving said bed from the latter to the former position, I mount on an extension of one of the bearings 21, a cylindrical casing 25 containing a coiled spring 26 preferably though not necessarily of the flat spiral type commonly used in clocks. The spring casing 25 is adjustably clamped to an extension of the bearing 21 by three 20 screws 27 and has one end of the spring 26 connected to it by a screw or pin 28. The opposite end of said spring is connected to a screw 29 mounted in a circular plate 30 forming part of or rigidly connected to a sleeve 31 keyed on the spindle 22 by a pin 32. The circular plate 30 forms the outer 25 portion of and serves as a closure for the spring casing 25, and its screw 29, which serves as a crank pin, has connected to it one end of a link 33 actuated by a reset 30 lever 34. Said lever has a head 35 at its forward end and is fixed to a spindle 36 journaled in the rear of the platform 10 so that it projects from the rear to the front 35 of said platform at one end thereof. The link 33 has an elongated slot 37 for the reception of a screw 38 mounted in the lever 34 and the latter is preferably maintained in and tends to return to a substantially horizontal 40 position under the action of a coil spring 39 mounted under the platform 10 and having one end connected to an arm 40 projecting from the spindle 36.

The spring 26 is so designed and adjusted 45 that through the crank plate 30 and spindle 22 it tends to move the bed 24, from the position in full lines in Fig. 1, to the position shown in dotted lines. The length of the slot 37 in the link 33 is such as to freely 50 permit of this movement of said bed with its attached parts. After such movement has occurred, however, downward pressure 55 upon the head 35 of the lever 34 will cause the screw 38 to engage the lower end of said slot 37 and thereafter the continued

downward movement of said lever through the link 33, plate 30, and sleeve 31 will swing the bed from its vertical position to its horizontal position, at the same time winding up the spring 26.

For releasably holding the bed 24 in its lower or horizontal position shown in Fig. 1, I provide a hook 41 fixed to a short shaft 42 journaled in the platform 10 and projecting beyond the end of the same immediately over the resetting lever 34. This projecting end of said shaft has fixed to it a forward and upwardly projecting arm 43 extending immediately adjacent the head 35 of the resetting lever, and a spring 44 coiled on the shaft has one end fixed to the same by a screw 45 so that the arm 43 is normally maintained in an upright position. At the same time, the hook 41 is at all times pressed inwardly so that it tends to remain in engagement with a horizontally projecting pin 46 mounted in the under side of the bed 24,—the arrangement being such that a depression of the arm 43 will free said hook from said pin, thus leaving the bed free to move under the action of the spring 26. The nose of the hook 41 is preferably inclined so that upon downward movement of the bed, the pin 46 will force said hook to one side and then be engaged by the same in such manner that the bed will be held in its lower position. The arm 43 preferably includes a hub or sleeve portion on the shaft 42 which is engaged by the resetting lever 34 so as to limit the upward movement thereof.

The top member 17 of the frame is provided with a cavity for a spring plunger 48 (Fig. 5) which normally projects from the front of the type housing in a position to be engaged by and serve to cushion the blow of, the bed 24 when this is released by the hook 41. For this purpose said plunger is normally pressed out by a spring 49 and is retained in its cavity by a pair of nuts 50 threaded on its rear end. For coacting with the plunger 48, I preferably mount in the bed a screw 51 (Fig. 1) and if desired on opposite ends of the top housing member 11 I provide a pair of adjustable stops in the form of screws 55 which effectually limit the approach of the bed to the type housing. The arrangement is such, however, that when under the action of the spring 26, the bed approaches the type housing, the screw 51 first strikes the end of the spring plunger 48 and forces this into its cavity until said bed is brought to rest by engagement of the label which it carries with the type ribbon and type. For making it possible for the type to print the label presented by the bed, I provide the back of the frame or standard 12 with parallel guides 58 on which a cross-head 59 is vertically slidable. This cross-head is fixed by a screw 60 to a rod 61 verti-

callly slideable in bearings in the frame 12 and table 10 and having fixed to its upper end a head or handle 62 whereby it may be manipulated. The cross-head 59 has oppositely projecting arms 63—63 whose ends extend around the opposite ends of the type housing and at their extremities have mounted upon them guide rollers 64 and 65. To the rear of these rollers and preferably 10 also to the rear of the type housing, said arms 63 respectively carry vertical posts 66 and 67 on which are rotatably mounted ribbon spools 66^a and 67^a; there being an inking ribbon 68 which passes from the spool 15 66^a on the post 66 around the guide rollers 64, hence across the face of the type housing, around the guide roll 65 to the spool 67^a on the post 67. When desired, the type in the housing may be exposed for purposes 20 for inspection or alteration by raising the cross-head 59 with its arms, rollers and inking ribbon for which purpose the head 62 is drawn upwardly. For holding the ribbon carriage with its attached parts in this 25 elevated position the rod 61 is provided with a notch 68 which, when said parts have reached their highest position, will be entered by one arm of a lever 69 pivoted to the frame 12 on a screw 70 and normally 30 pressed toward said rod by a spring 71. For positioning the ribbon carriage at the lower end of its possible range of movement, I fix to the rod 61, preferably immediately under its head 62, a projecting arm 72 carrying an adjustable screw 73 arranged to 35 strike the top member 17 when the ribbon carriage has been lowered sufficiently to properly position the ribbon 68 in front of the type α . By adjusting this screw, fresh 40 parts of the ribbon may be brought into position to engage the type.

For feeding the ink ribbon longitudinally from one of the spools 66^a to the other spool 67^a, the latter is fixed in any desired manner 45 to a ratchet wheel 75 which coacts with a pawl 76 mounted adjacent one end of a lever 77 fulcrumed at 78 to one of the arms 63 of the ribbon carriage. Said pawl is at all times pressed toward the ratchet by a suitable 50 spring and the lever 77 is actuated from the oscillatory bed through a swinging arm 79 and a lever 80 pivoted to the end of the frame 12 by a screw 81. The oscillatory bed adjacent its right hand end has a lug 82 55 in which is mounted an adjustable screw 83 and the latter is so positioned that when said bed is moved into its lower or horizontal position, the end of said screw engages a part of the lever 80, swinging it rearwardly 60 sufficiently to cause a projection 84 thereon to strike the swinging arm 79 so that this moves the lever 77 with the pawl 76 toward the ratchet wheel 75, causing the latter to be turned to the extent of one tooth of said 65 wheel. A spring pawl 85 is also provided

on the ribbon carriage to prevent backward movement of the ratchet wheel with its ribbon spool and the arrangement is such that each time the oscillatory bed 24 is swung down, it causes a predetermined rotation of 70 the spool 67^a and a definite feeding of the ink ribbon from the spool 66^a across the face of the type. It will be noted from Fig. 3 that the swinging arm 79 presents a straight vertical edge to the projection 84 of the 75 lever 80, so that all of the ribbon operating parts remain in their operative positions regardless of the position of the ribbon carriage.

As shown in Fig. 3, I mount a guide plate 80 or delivery chute 90 under the opening 20 of the platform 10, and curve this downwardly and forwardly from said opening so that labels falling from between the type housing and the bed are delivered at the 85 front of the base structure. The flat upper face of the bed 24 is preferably covered by a sheet or plate of soft rubber 91 having over it a thin sheet of paper or card board 92 held in place by a gauge plate 93 and a 90 pair of pins 94 placed in opposite corners of the inner edge of the bed. The gauge plate as illustrated has a downwardly extending portion engaged by an adjusting screw 95 threaded into the bed from the 95 outer edge thereof, in order to permit of the accurate placing of a label on said bed.

At one end of the platform 10, I preferably provide a table 96 in the form of a flat plate mounted to swing with a vertical post 100 97 rotatably mounted in said platform, and the arrangement is such that when the bed 24 is in its lower or horizontal position, said table may be turned into a position immediately over and substantially parallel with 105 said bed, thus preventing this from swinging to its upper or vertical position.

In order to utilize the above machine, the ribbon carriage is moved to its upper position by drawing the rod 61 upwardly, thus exposing the cavity of the type box and making it possible to mount therein any desired type. After this latter with suitable spacing strips, etc., has been clamped in the type box by setting up the screws 18, the 110 ribbon carriage is lowered after the lever 69 has been depressed to release the rod 61; it being assumed that the bed is in its lower or horizontal position shown in Fig. 3. The gauge plate 93 is now set and a label is 115 placed on the top face of said bed with one long edge underlying the inner straight edge of the gauge plate 93 and in engagement with a strip 98 integral with the plate 93; its left hand end being in engagement with a right angle projection 99 of the auxiliary gauge strip 98. If the arm 43 be now 120 depressed, the hook 41 is disengaged from the pin 46, and under the action of the spring 26, the bed 24 is swung upwardly, causing 125 130

the label to be pressed against the ink ribbon and the latter in turn to be forced against the type,—the spring plunger 48 being moved inwardly against its spring 49 sufficiently to permit of this action. Said spring, however, shortly thereafter expands, moving the bed outwardly a short distance away from the type and thereby releasing the printed label which falls through the opening 20 into the chute 90, whereby it is delivered at the front of the machine. A downward pressure on the head 35 of the resetting lever 34 now swings the bed downwardly from its upper to its lower position, where its pin 46 is engaged and held by the spring actuated hook 41. This downward movement of the bed through the screw 83 turns the ribbon spool 67^a to a limited extent and winds up a short length of the ink ribbon, thus bringing a fresh portion of the latter over the face of the type. If desired, I may mount a counting device 100 on the rear part of the platform 10 and connect the actuating lever thereof with a suitable part of the oscillatory bed through a link 101 (Fig. 1), so that each oscillation of said bed will operate said instrument. From the above description, it will be appreciated that my device is not only easy and convenient to manipulate, but its construction is such as to require a minimum of skill and attention for such operation. Moreover, its parts are so arranged that if desired, it may be run at a high speed and caused to print large numbers of labels all with the highest degree of accuracy; the arrangement of the releasing and resetting levers being such as to permit of their quick and convenient operation by one hand, while the operator's other hand is engaged in placing labels on the bed and removing printed labels from the bottom of the chute.

It is to be noted that the spring 26 is preferably so set that it is practically tensionless when the bed is in its upper or vertical position, although obviously the tension may be very conveniently adjusted by loosening any one of the three screws 27 and shifting the position of the spring casing 25 in one direction or the other, thereafter tightening said screw 27 which had been loosened.

While I have shown the type housing so positioned that the printing faces of the type are in a vertical plane, and have also shown the bed as movable to such a position that its face is horizontal when a label is to be applied thereto, it will be understood that without departing from my invention these elements may occupy other angular positions, so that the type housing is positioned to permit of the ready insertion and adjustment of the type, and the bed when in its lower position has its upper face conveniently available for the reception of the labels to be printed.

In order to bring different transverse portions of the inking ribbon into position to engage the type so that practically all portions of said ribbon will be utilized, I raise or lower the said ribbon through its supporting carriage by adjusting the screw 73,—this adjustment being preferably made after the entire length of the ribbon has been passed across the type. When said ribbon has thus been all wound on the spool, the two ribbon spools are reversed upon their supporting spindles, and the screw 73 is turned to move the ribbon relatively to the type.

While I have described my machine as particularly designed for hand operation, it is obvious that the two levers 34 and 43 may be actuated automatically by power from a suitable mechanical source without departing from my invention. Moreover, as shown in Fig. 7, I may cause the machine to operate through a complete cycle by the use of but a single reversing lever. For this purpose, in place of the lever 43 projecting forwardly and upwardly, I provide an arm 43^a fixed to the spindle 42 and projecting rearwardly and down so that it is engaged by the lever 34 and moved up sufficiently to cause the hook 41 to disengage the pin 46 after said lever has been released from its lower position.

With this arrangement of parts, the depression of the lever 34 moves the bed 24 to its horizontal position and allows the placing thereon of the label to be printed,—the bed as before being retained in its lower position by the hook 41. Upon release of the lever 34, the spring 39 forcibly returns it to its upper position, bringing it into engagement with the arm 43^a and causing this to release the hook 41 from the pin 46. The bed is thus free to move under the action of the spring 26 to present the label to the type and cause it to be printed and thereafter discharged. Thereafter the depression of the lever 34 will again return the bed to its lower position ready to receive another label.

I claim:

1. The combination in a printing machine of type; a pivotally mounted bed; a spring device for propelling the bed toward the type; and a member normally holding the bed away from the type with the spring device under tension.

2. The combination in a printing machine of type; a pivotally mounted bed; a spring device for propelling the bed toward the type; a member normally holding the bed away from the type with the spring device under tension; and a member for resetting the bed after it has moved toward the type.

3. The combination in a printing machine of type; a swinging bed; a spring for swing-

ing the bed toward the type; a hand operated member for moving the bed away from the type and at the same time placing the spring under tension; with means for releasably holding the bed away from the type.

4. The combination in a printing machine of a supporting frame; means on the frame for holding type with their faces in a substantially vertical plane; a bed hinged to the frame and having a flat face for presenting a label to the type; a spring for moving said bed from a substantially horizontal position into position to present a label to the type; and a member for releasably holding the bed in a substantially horizontal position against the action of the spring.

5. The combination in a printing machine of a supporting frame; means on the frame for holding type with their faces in a substantially vertical plane; a bed hinged to the frame and having a flat face for presenting a label to the type; a spring for moving said bed from a substantially horizontal position into position to present a label to the type; and a member for releasably holding the bed in a substantially horizontal position against the action of the spring; with a second member for returning said bed to its horizontal position.

6. The combination in a printing machine of a supporting frame; means on the frame for holding the type; a bed hinged to the frame and having a label receiving face; a spring for moving the bed from a substantially horizontal position into a position to present a label to the type; a hook for holding the bed in its substantially horizontal position against the action of the spring; and means for actuating the hook to release the bed.

7. The combination in a printing machine of a supporting frame; means on the frame for holding type; a bed hinged to the frame and having a label receiving face; a spring for moving the bed from a substantially horizontal position into a position to present a label to the type; a hook for holding the bed in its substantially horizontal position against the action of the spring; with a hand operated member for moving the hook to release the bed.

8. The combination in a printing machine of a supporting frame; means on the frame for holding type; a bed hinged to the frame and having a label receiving face; a spring for moving the bed from a substantially horizontal position into a position to present a label to the type; a hook for holding the bed in its substantially horizontal position against the action of the spring; means for actuating the hook to release the bed; with a second member for resetting the bed in its horizontal position in engagement with the hook.

9. The combination in a printing machine of type; a pivotally mounted bed; an inking ribbon extending across the face of the type; a spring for propelling the bed toward said ribbon and the type; and a member normally holding the bed away from the type with the spring under tension.

10. The combination in a printing machine of type; a pivotally mounted bed; an inking ribbon extending across the face of the type; a spring for propelling the bed toward said ribbon and the type; a member normally holding the bed away from the type with the spring under tension; and means actuated by the movement of the bed for periodically feeding the ribbon relatively to the type.

11. The combination in a printing machine of type; a swinging bed; a spring for propelling the bed toward the type; a member for releasably holding the bed away from the type with the spring under tension; means for swinging the bed away from the type; an inking ribbon extending across the face of the type; and mechanism actuated by the bed when it is moving away from the type for feeding the inking ribbon relatively to said type.

12. The combination in a printing machine of type; a swinging bed movable toward and from said type; a spring for forcibly moving the bed toward the type; a member for normally holding the bed away from the type; and two adjacent members for actuating the holding member and for moving the bed away from the type respectively.

13. The combination in a printing machine of type; a bed movable toward and from the type; a spring connected to propel the bed toward the type; a member for holding the bed away from the type against the action of the spring; and two levers adjacent each other connected to respectively actuate the holding member and to move the bed away from the type.

14. The combination in a printing machine of means for supporting type; a swinging bed movable toward and from said type; a crank connected to said bed; a spring operative on the bed to forcibly propel it toward the type; and a member connected to said crank for resetting the bed in a position removed from the type after the spring has moved it toward the same.

15. The combination in a printing machine of means for supporting type; a swinging bed movable toward and from said type; a crank connected to said bed; a spring operative on the bed to forcibly propel it toward the type; and means connected to said crank for resetting the bed in a position removed from the type after the spring has moved it toward the same, comprising a slotted link connected to said crank

- and a lever having a pin operative in said slot.
16. The combination in a printing machine of a supporting structure including a platform; a type housing; a bed hinged to said platform and movable toward and from the type housing; a spring connected to the bed so as to be placed in tension by movement of the bed away from the type; a member mounted on the platform for holding the bed away from the type with the spring under tension; and a hand operated element for moving said member to release the bed at will.
17. The combination in a printing machine of type supporting means; a swinging bed movable toward and from said means; and having a pivot spindle; a spring adjustably connected to said spindle and placed under tension when the bed is moved away from the supporting means; and a device for holding said bed at will in a position removed from the type supporting means with the spring under tension.
18. The combination in a printing machine of type supporting means; a swinging bed movable toward and from said means and having a pivot spindle; a spring adjustably connected to said spindle and placed under tension when the bed is moved away from the supporting means; a device for holding said bed at will in a position removed from the type supporting means with the spring under tension; and a hand operated crank for holding the bed away from the type holding means after the spring has operated.
19. The combination in a printing machine of a substantially horizontal platform having an opening therein; means for holding type above said opening; a swinging bed; a spring for moving said bed to present a label to the type; and a device for automatically moving the bed away from the type after the spring has caused it to present a label thereto be permit said label to fall through said opening under the action of gravity.
20. The combination in a printing machine of a substantially horizontal platform having an opening therein; means for supporting type above said opening; a swinging bed; a spring for moving said bed to present a label to the type; and a device for automatically moving the bed away from the type after the spring has caused it to present a label thereto, to permit said label to fall through said opening under the action of gravity; with a delivery chute for receiving the label from the opening.
21. The combination in a printing machine of means for supporting type with their printing faces substantially vertical; a pivotally mounted bed; a spring for forcibly swinging said bed toward the type to present a label thereto; and a spring actuated element for moving the bed a short distance away from the type to release the label after its presentation thereto.

PAUL DIETZ.
